(57) **CLAIM**

The ornamental design for a laundry bin as shown and described.

DESCRIPTION

FIG. 1 is a perspective view of the laundry bin showing my new design;

FIG. 2 is a side view thereof;

FIG. 3 is another side view thereof;

FIG. 4 is a top plan view thereof;

FIG. 5 is a top plan view thereof with the lid portion removed;

FIG. 6 is a bottom plan view thereof;

FIG. 7 is another side view of the laundry bin in an assembled state;

FIG. 8 is another side view thereof; and,

FIG. 9 is an exploded perspective view of the laundry bin in a disassembled state.

The broken lines in the drawings illustrate portions of the laundry bin which form no part of the claimed design.

1 Claim, 9 Drawing Sheets
